UNITED STATES PATENT OFFICE.

HENRY J. MICHAELSEN, OF TACOMA, WASHINGTON.

METAL-BENDING DEVICE.

Application filed July 7, 1925. Serial No. 42,083.

The present invention relates to metal bending devices and more particularly to a hand implement for use about small machine shops and the like.

5 An object of this invention is to provide a device for rolling or bending the end of a spring to form an eye such as is used in automobile spring construction so that a mechanic can easily and quickly make a repair 10 to an automobile spring and substitute leaves therefor from stock material.

Another object is to provide a machine which may be adjusted to accommodate stock bars of different thicknesses and which may 15 also be adjusted to form eyes on the ends of the bars of different diameters or of the same diameter with stock of different thicknesses.

A further object of the invention is to 20 provide a reciprocating handle with a gripping portion capable of being moved toward and from the work according to the thickness thereof and which when adjusted may then be swung on the arc of a circle to bend 25 the material, and may be retracted to obtain a new grip on the material for further bending until the eye formation is complete.

A still further object of the invention is 30 to provide a portable hand operated and adjustable device of this character which may be economically manufactured, which is light in weight, and which may be easily set up for use without special support or special attachments.

35 The above and various other objects and advantages of this invention will in part be described in, and in part be understood from, the following detailed description of the present preferred embodiment, the same being illustrated in the accompanying drawings, wherein:

Fig. 1 is a vertical longitudinal section taken through a bending device constructed according to the present invention, a bar of 45 stock material being shown in initial position therein.

Fig. 2 is a top plan view of the same, partly in section.

Fig. 3 is a transverse section taken on the 50 line 3-3 of Fig. 1.

Fig. 4 is a similar view taken on the line 4-4 of Fig. 1.

Fig. 5 is a reduced longitudinal section taken through the device showing in full 55 lines the position of the movable parts upon completion of a stroke thereof and showing

in dotted lines the initial position of the movable parts, the view showing an eye completed in the stock bar material.

Fig. 6 is a detail perspective view of a 60 core pin used for determining the inside diameter of the eye, and

Fig. 7 is a similar view of a slightly modified form of core pin of less diameter to form 65 a smaller eye.

Referring to the drawings 10 designates a frame which is substantially of channelled or U-shape construction and whose side pieces extend upwardly to receive the operating parts therebetween. As shown, the 70 outer end of the frame 10 may be of deeper construction than the inner end thereof for the purpose of facilitating the introduction and removal of the work, shown in the present instance as a flat bar 11 of stock material adapted to be bent or curved at one 75 end into an eye construction.

Pivoted to swing in the forward end of the frame 10 is a reciprocating member comprising a pair of side plates 12 which are of 80 relatively wide construction at their lower ends, and which may be of reduced width at their upper ends. The wide ends of the plates 12 are apertured to receive therethrough bushings 13 which are mounted in 85 the sides of the frame 10 and provide pivot supports for the arms 12. The outer ends of the arms 12 are connected together by a cross bar 14 which is provided with a transverse opening therethrough for the purpose 90 to be presently described.

A hand lever 15 is fitted at its lower end between the intermediate portions of the plates 12 and is provided at its rear side and lower end with an offset pivot eye 16 95 through which is fitted a rod 17 carried by the plates 12 to pivotally support the handle 15. Extending forwardly from the pivot 16 and from the inner end of the hand lever 15 is an arcuate claw 18 with a ratchet toothed lower surface with the teeth facing outwardly adapted to engage the upper surface of the stock 11 for binding against it when the handle 15 is swung forwardly.

100 A core pin 19 is removably fitted across the frame 10 in the bushings 13 and is given suitable dimensions at opposite ends to closely fit the bushings 13. The intermediate portion of the pin 19 is so proportioned as to diameter as to engage and bear against 105 the under side of the stock 11 and support it against pressure of the claw 18. The core 110

pin 19 is removable and provided upon one end with a finger hold or ring 20 by means of which the pin may be withdrawn and inserted. To determine the positioning of the pin the end adjacent the finger hold 20 may have an enlarged head 21, and the adjacent bushing 13 may be of corresponding size to receive it, while the inner end 22 of the pin may be of smaller diameter and the adjacent bushing 13 correspondingly reduced.

10 The core pins 19 may be of different sizes as to their central portions so as to accommodate stock 11 of different thicknesses and to form eyes of different diameters, and in Fig. 15 7 is shown one modification of core pin 23 which has a reduced intermediate portion as compared with the pin 19.

15 The handle 15 is provided with an opening 24 therethrough adapted to register with the opening 25 in the cross bar 14, and a bolt 26 is loosely fitted through the openings 24 and 25 and provided thereon with a coil spring 27 lying between the hand lever 15 and the cross bar 14 to normally urge the 20 same apart. A winged nut 28 is threaded upon the rear end of the bolt 26 and bears against the rear side of the cross bar 14 to draw the bolt backwardly through the hand 25 lever 15 and the cross bar 14 and bind the head of the bolt 26 against the forward side of the hand lever 15. As shown in dotted 30 lines in Fig. 1 the winged nut 28 may be adjusted lengthwise of the bolt 26 to vary the distance between the hand lever 15 and the bar 14. This distance is adjusted to bring the claw 18 against the work when the 35 reciprocating member is swung backwardly to its initial position and to take up the play between the hand lever 15 and the reciprocating member when the hand lever is drawn forwardly and downwardly to bend the stock 11 about the core pin 19.

40 In order to hold the rear portion of the stock 11 from rising during the bending operation, the frame 10 may be provided with a pair of upstanding ears 29 for receiving a cross pin 30 which is selectively positioned in registering openings 31 formed in the ears.

45 50 In operation the selected core pin 19 is inserted in the frame concentrically to the reciprocating member. The bar 11 is fitted under the pin 30 and upon the upper side of the core pin 19. The winged nut 28 is adjusted along the bolt 26 to swing the hand lever 15 and bring the claw 18 into proper contact with the upper surface of the stock 11. The hand lever 15 is now swung forwardly into the full line position shown in 55 Fig. 5, such as to bind the stock upon the core pin and draw the stock forwardly and bend it downwardly against the outer surface of the pin. The reciprocating member is now returned to initial position as shown 60 in dotted lines in Fig. 5, and the operation 65

repeated with the claw 18 engaging the succeeding portion of the stock 11. The reciprocating member and the hand lever 15 is thus worked back and forth until the complete eye is formed, or the curvature carried 70 out to the desired extent.

75 The claw member 18 together with the hand lever 15 provides a gripping member which is carried by the reciprocating member and which is initially operated prior to the advance of the reciprocating member, and which is released by the sliding of the bolt 24 through the lever 15 and bar 14 when the spring 27 is compressed during the initial backward movement to retract the reciprocating member. The openings 31 in the ears 29 may be carried through the sides of the frame 10 as shown in Fig. 3 so that the bar 30 may be inserted through the ears 80 from either side of the device.

85 It is of course understood that various changes and modifications may be made in the details of construction and design of the above specifically described embodiment of this invention without departing from the spirit thereof, and being restricted only by the scope of the following claims.

What is claimed is:

1. A spring eye bender comprising a frame, a pin mounted in the frame, a pivotal member on the pin, a lever mounted on the pivotal member and adapted to turn therewith, a claw secured to said lever and at the forward end thereof, adjusting means for said claw, and a spring interposed between said lever and said adjusting means for insuring the initial gripping of the claw.

2. A spring eye bender comprising a frame, a pin in the frame, a reciprocating member mounted on the pin and adapted to swing therearound, a claw pivotally mounted on said reciprocating member, adjusting means for said claw, yieldable means adapted to insure the initial gripping of said claw prior to the forward movement thereof, and a lever secured to said claw for swinging the claw and the reciprocating member about the pin.

3. An automobile spring eye bender, comprising a frame, a removable core pin mounted in the frame for supporting the end of a stock bar, a reciprocating member pivotally mounted on the frame, concentric to the core pin, a hand lever pivoted on the reciprocating member, a claw projecting forwardly from the pivoted end of said lever and adapted to bind against the upper side of said bar, a bolt adjustably connecting the lever with the reciprocating member, and a spring interposed between the lever and the reciprocating member for insuring the initial gripping of the work against the core pin prior to the movement of the reciprocating member by said handle.

4. A metal eye bender comprising a frame,

a work support pin in the frame, a reciprocating member mounted on the pin, a claw pivoted to said reciprocating member, a bolt connecting the upper end of said claw and said reciprocating member for adjusting the claw with respect to said pin, and a spring mounted on said bolt and between the claw and the reciprocating member for insuring the initial gripping of the claw.

5 10 5. A metal eye bender comprising a frame, a core pin removably mounted in the frame,

a reciprocating member adapted to swing about said core pin, a claw pivoted to said reciprocating member, adjustable means for said claw, and a spring mounted on said adjustable means and between the claw and reciprocating member for insuring the gripping of the claw upon the work prior to the swinging of the reciprocating member about the core pin.

15 HENRY J. MICHAELSEN.
